Primary Examiner — Prabhakar Deshmukh(74) *Attorney, Agent, or Firm* — Robin S. Fahlberg(57) **CLAIM**

The ornamental design for a key, as shown and described.

DESCRIPTION

FIG. 1 is a front view of a key showing our new design; FIG. 2 is a right view thereof; FIG. 3 is a back view thereof; FIG. 4 is a left view thereof; FIG. 5 is a top view thereof; FIG. 6 is a bottom view thereof; FIG. 7 is a front perspective view thereof; and, FIG. 8 is a back perspective view thereof. The broken lines of the figures showing additional portions of the key are included for the purpose of illustrating environmental structure and form no part of the claimed design.

It is certified that error appears in the above-identified patent and that said Letters Patent is hereby corrected as shown below:

Delete the title page and substitute therefore the attached title page consisting of the corrected
illustrative figure.

Delete Drawing Sheets 1-8 and substitute therefore the attached Drawing Sheets 1-8.

Signed and Sealed this
Fourth Day of September, 2012

David J. Kappos
Director of the United States Patent and Trademark Office
